NORTON A. MEARS AND DIBRELL P. HYNES, OF CHICAGO, ILLINOIS, ASSIGNORS TO
CHICAGO FORGING & MANUFACTURING CO., OF CHICAGO, ILLINOIS, A CORPORATION
OF ILLINOIS

HOOD LATCH

Original application filed May 10, 1929, Serial No. 361,932. Divided and this application filed April 29, 1931. Serial No. 533,661.

Our invention relates to locking or latching means for closures and is herein shown as applied to an automobile hood. One purpose is the provision of simple and easily operated means for securing an automobile hood in closed position. Another object is the provision of means for drawing the hood downwardly and inwardly against its abutment on the frame of the automobile. Another object is the provision of means for permitting the actuation of a plurality of hood latching means by a single handle adapted both to latch and unlatch the hood and to raise and lower the hood. Other objects will appear from time to time in the course of the specification and claims.

The invention is illustrated more or less diagrammatically in the accompanying drawings, wherein—

- 20 Figure 1 is a side elevation;
- Figure 2 is an interior elevation;
- Figure 3 is a section on the line 3—3 of Figure 2;
- Figure 4 is a section on the line 4—4 of 25 Figure 2;
- Figure 5 is a section on the line 5—5 of Figure 2;

Figure 6 is a view similar to Figure 2 illustrating the device in unlocked position.

30 Like parts are indicated by like symbols throughout the specification and drawings.

Referring first to Figures 1 and following, A generally indicates the body of the vehicle and A¹ a hinged hood member. A² indicates the vehicle frame, and A³ a hood abutment secured thereto. A⁴ A⁴ indicate terminal abutments for the ends of the hood. Mounted within the hood is a rock shaft generally indicated as B having the terminal 40 recurved portions B¹ B¹ which are received in bearings B⁴ B⁴ on the interior of the hood. It will be observed that no bearings are shown between the bearings B⁴ and the intermediate bearings B⁵ adjacent the central 45 portion of the rod. It will be understood that additional bearings may be interposed if necessary. The recurved portion B¹ is connected with the body of the rod by a short stretch B¹¹ which, when taken in connection 50 with the adjacent portions of the rod B, serves

as a crank arm for engaging any suitable latch abutments B² B² herein shown as mounted on the members A⁴, having the faces B³ inclined upwardly and inwardly from the hood. B¹² indicates a projection at the upper end of each such face. Between the central members the rock shaft is indicated as offset or deformed as at B⁶, this offset portion including what may be called a cam portion B⁷ which may be more or less curved as shown for example in Figure 4.

C indicates a shaft with the exterior handle C¹, the shaft passing through the hood. At its inner end is mounted the cam member generally indicated as C² which may have the hook or horn C³ adapted to cooperate with the portion B⁷ of the offset B⁶. It is further provided with an apron B⁸ which, when the device is in locking position, as shown in Figure 2, overlies the offset portion and constrains it to the full line position of Figure 4. The flange B⁹ of the apron B⁸ engages the side B⁷ of the offset and limits further counter-clockwise movement, locking the parts in the position in which they are shown in Figure 2. 75 This limit is preferably so arranged that at that position the handle C¹ is horizontal, for convenience. It will be understood that when the parts are in the full line position in which they are shown in Figure 2 the offsets or crank arms formed by the ends of the shaft B in connection with the end members B¹¹ are thrust into locking engagement with the inclined edges B³ of the abutments B² and the result is the drawing downwardly and inwardly of the lower edge of the hood. B¹⁰ indicates a depression in the apron B⁸, adapted to hold the parts locked, when it engages the portion B⁷.

90 Taking the parts for example in the position in which they are shown in Figure 2, when the device is rotated clockwise, the horn C³ engages the offset B⁷ and exerts a camming action against its lower inclined portion and thus rotates the entire rock shaft in such fashion as to withdraw the cranks B¹¹ from the abutments B². The cam body and apron B⁸ are so proportioned as to limit the rotation of the handle to an arc of 180 degrees, in such fashion that the handle is in 95 100

horizontal position when the cranks B¹¹ have been removed to inoperative position and is therefore in the most convenient position for the manual lifting of the now released hood.

5 It will be realized that whereas we have described and shown a practical and operative device, nevertheless many changes might be made in the size, shape, number and disposition of parts without departing from the 10 spirit of our invention. We therefore wish our description and drawings to be taken as in a broad sense illustrative and diagrammatic rather than as limiting us to our specific showing.

15 The present application is a division of applicants' co-pending application Serial Number 361,932, filed on the 10th day of May, 1929.

20 The use and operation of our invention are as follows:

25 In securing the hinged hood portions of automobiles and the like, securing means are desirable which hold the hood firmly in position, which draw the lower edge of the hood downwardly, to hold it tight, and which also draw it inwardly or prevent it from outward movement. We have provided means for effecting these results which are simple and efficient and which respond to the movement 30 of a single handle member. This handle member, being preferably situated midway between the ends of the hood, not only serves to control the hood latching means, but also serves as a handle for lifting the hood when 35 the latches are disengaged. We preferably employ a handle of somewhat elongated form, to serve conveniently as a lifting as well as a turning means. We preferably so proportion the parts that the handle C¹ is in 40 generally horizontal position when the latch members B¹ are disengaged. We find it convenient to limit the rotation of the handle to an arc of 180 degrees, whereby the handle is also in horizontal position when the hood is 45 latched.

50 In order to provide simple means for latching the hood in position we employ a rock shaft the ends of which may be bent or deformed to form crank arms or the equivalent of crank arms. In other words some part of the rock shaft, preferably the end is so far offset from the center of rotation of the body of the rock shaft, that rotation of the rock shaft imparts such movement to the end or 55 ends as will cooperate with a latch abutment to have the desired locking effect. Preferably in order to form the crank arms or crank portions we provide the terminal recurved portions B¹ which are received in the bearings B⁴ on the interior of the hood. It will be observed that no bearings are shown between the bearings B⁴ and B⁵. The recurved portion is connected to the body of the rod by a short stretch which, when taken in connection with the adjacent portions of the

rod B, serves as a crank arm for engaging the abutments B¹².

60 In response to a locking rotation of the handle C¹ the crank ends of the rock shaft are given what in Figures 4 and 5 would be a 70 clockwise rotation. They engage the inclined surfaces B⁸ and the result is a camming effect whereby further rotation of the rock shaft tends to draw the lower edge of the hood both inwardly and downwardly. The shaft 75 being flexible and being provided with relatively long spaces which are free from restricting bearings, a certain spring action or play is permitted which adds to the locking effect and at the same time compensates for 80 irregularities and prevents undue strain on any part of the device. It is necessary to make the edge B⁸ of sufficient length to engage the crank arms B¹¹ throughout a reasonable range. This provides for irregularities 85 in dimension and form of the various parts and also for irregularities in assembly of the parts. The member B¹² serves as an upper stop to prevent any possible overriding of the 90 crank arms B¹¹ over the inclined edge B⁸. 95

The recurved form of crank arm we find to be particularly advantageous owing to the fact that the bearings for the ends of the rock shaft may be generally aligned with the point of engagement of the crank arms and the 95 abutment edges B⁸. The result is a particularly firm locking effect with a minimum of undesired play or spring, and a freedom from rattling.

100 We claim:

1. A latching device for an automobile hood which includes a plurality of latch abutments within the hood and laterally inwardly spaced therefrom when the hood is in closed position, a rock shaft adapted to be supported upon the interior of said hood, said shaft having an intermediate offset portion, a cam member, adapted to engage said offset portion, rotatably mounted within and upon the hood, an exterior handle adapted to rotate said cam member, and additional portions on said shaft adapted to engage said latch abutments and bearings interposed between the ends of the rock shaft and the hood, the ends of the rock shaft, adjacent said last mentioned portions, being recurved toward the intermediate portion of the shaft, to engage said bearings. 110 115

2. A latching device for an automobile hood which includes a plurality of latch abutments positioned within the hood and laterally inwardly spaced therefrom when the hood is in closed position, a rock shaft adapted to be supported upon the interior of the hood, and means for rotating it, and offset portions on said rock shaft adapted to engage said latch abutments, said abutments being provided with edges, upwardly and inwardly inclined from the plane of rest of the hood, adapted to receive the offset portions 120 125 130

of the rock shaft when they are rotated into locking position, the ends of said rock shaft being recurved adjacent said abutments, and supporting means for rotatably securing said 5 recurved ends of the rock shaft to the hood.

3. A latching device for an automobile hood which includes a plurality of latch abutments positioned within the hood and laterally inwardly spaced therefrom when 10 the hood is in closed position, a rock shaft adapted to be supported upon the interior of the hood, and means for rotating it, and offset portions on said rock shaft adapted to engage said latch abutments, said abutments being provided with surfaces upwardly and inwardly inclined from the plane of rest of the hood, adapted to receive the offset portions of the rock shaft when they are rotated into locking position, the ends of said 15 rock shaft being recurved adjacent said abutments, and bearing, supporting means for rotatably supporting said recurved ends of the rock shaft to the hood, said bearing means substantially aligned with the plane 20 of engagement of the offset portions of the rock shaft with the latch abutments.

4. A latching device for an automobile hood which includes a plurality of latch abutments positioned within the hood and laterally inwardly spaced therefrom when the 25 hood is in closed position, a resilient rock shaft adapted to be supported upon the interior of the hood, the ends of said rock shaft being recurved and secured rotatably to said 30 hood the portions of the shaft adjacent such recurved portions being aligned with said latch abutments, and means for rotating said rock shaft to thrust said portions thereof into latching engagement with said latch abutments.

5. A latching device for an automobile hood which includes a plurality of latch abutments positioned within the hood, a rock shaft adapted to be supported upon the interior of the hood and means for rotating it, and supporting bearings for said rock shaft, adjacent the middle of the rock shaft and at the two ends, the portions of said shaft intermediate said middle and terminal bearings being 45 flexed or offset.

6. A latching device for an automobile hood which includes a plurality of latch abutments positioned within the hood, a rock shaft adapted to be supported upon the interior of the hood and means for rotating it, terminal supporting bearings for the rock shaft, the ends of said rock shaft being recurved toward the center of the shaft, said recurved end portions being in engagement with the terminal 55 supporting bearings for the rock shaft, intermediate portions of said rock shaft being laterally offset from said recurved end portions, said intermediate portions and end portions being connected by portions of the rock shaft 60 positioned beyond said terminal bearings.

7. A latching device for an automobile hood which includes a plurality of latch abutments positioned within the hood, a rock shaft supported upon the interior of the hood and means for rotating it, terminal supporting 70 bearings for the rock shaft, intermediate bearing means for the rock shaft, said bearings being aligned along the axis of rotation of the shaft, the ends of the rock shaft being recurved toward the center of the shaft, said recurved end portions being in engagement with the terminal supporting bearings for the rock shaft, the intermediate portions extending inwardly from said recurved portions being out of line with and inclined in relation to the axis of rotation of the rock shaft as a whole.

8. A latching device for an automobile hood which includes a plurality of latch abutments positioned within the hood, a rock shaft supported upon the interior of the hood and means for rotating it, terminal supporting 85 bearings for the rock shaft, intermediate bearing means for the rock shaft, said bearings being aligned along the axis of rotation of the shaft as a whole, the ends of the rock shaft being recurved toward the center of the shaft, said recurved end portions being in engagement with the terminal supporting bearings for the rock shaft, the intermediate portions 90 extending inwardly from said recurved portions being out of line with and inclined in relation to the axis of rotation of the rock shaft as a whole, and an actuating member, adjacent the intermediate bearing means, the 95 rock shaft rotating means being adapted to cooperate with said member.

9. A latching device for an automobile hood which includes a plurality of latch abutments positioned within the hood and laterally inwardly spaced therefrom when the hood is in closed position, a rock shaft adapted to be supported upon the interior of the hood, and means for rotating it, and offset portions on said rock shaft adapted to engage said 100 latch abutments, said abutments being provided with surfaces upwardly and inwardly inclined from the plane of rest of the hood, adapted slidably to receive the offset portions of the rock shaft when they are rotated 105 into locking position, the ends of said rock shaft being recurved adjacent said abutments, and bearing supporting means for rotatably securing said recurved ends of the rock shaft to the hood, said bearing means being adjacent the points of engagement of the offset 110 portions of the rock shaft with the latch abutments.

Signed at Chicago, county of Cook and State of Illinois, this 24th day of April, 1931. 115
